TELEPHONE INSTRUMENT CIRCUIT

George William Sutton, London, and William Herbert Grinsted, Bromley, England, assignors to Siemens Brothers & Company Limited, London, England

Application June 22, 1936, Serial No. 86,568
In Great Britain July 1, 1935

4 Claims. (Cl. 179—81)

The present invention relates to telephone instrument circuits, and more particularly to circuit arrangements for use with variable-resistance transmitters or microphones of the differential type.

By a variable-resistance microphone of the differential type is meant one which comprises what are in effect two microphone elements, these elements being arranged so that during the operation of the microphone the resistance of one element is increased as the resistance of the other is decreased, and vice versa. Such microphones are usually (but not necessarily) of the kind in which a single moving electrode is situated between two fixed electrodes, the two microphone elements being formed by the variable-resistance path between the moving electrode and one fixed electrode and the variable-resistance path between the moving electrode and the other fixed electrode.

According to the invention, the circuit of a variable-resistance microphone of the differential type is such that direct current which passes for feeding purposes through either half or microphone element of the microphone must also pass through the other half or microphone element irrespective of whether or not the resistances of the two halves or elements are equal in value. The provision of this feature helps to maintain the two halves of the transmission system in balance.

In carrying out the invention, we arrange that the two halves or microphone elements of the microphone are connected in series across leads connected directly or indirectly to a battery or other source of microphone feeding current, and also arrange that the passage of direct current through an output circuit (e. g. the primary winding of a transformer) connected to the junction between the two elements (e. g. connected to the moving electrode of a microphone comprising two fixed electrodes and an intermediate moving electrode) is blocked by one or more condensers. The said condenser or condensers may be arranged to play an important part in determining the response-frequency characteristic of the microphone system. For example, it may be arranged that a high-pass filter effect is obtained, so that the microphone system provides good speech articulation but does not transmit low-frequency room noise efficiently.

In one arrangement which may be employed in practice, two condensers of equal capacity connected in series and the two halves or microphone elements of the microphone connected in

series together form the arms of a four-armed bridge, a circuit for feeding direct current to the microphone being connected to the two junction points where a condenser is connected to one of the said halves or elements and an output circuit (e. g. the primary winding of a transformer) being connected to the other pair of junction points.

In another arrangement which may be employed in practice, the two halves or microphone elements of the microphone are connected in series across a battery, and the junction between the two elements is connected via an output circuit (e. g. the primary winding of a transformer) and a condenser connected in series to the centre point of the battery.

The features of the invention are exemplified in the specific embodiments of it which will now be described with reference to the accompanying drawing. Fig. 1 of the drawing shows a subscriber's instrument circuit arranged for central battery working and Fig. 2 shows a subscriber's instrument circuit arranged for local battery working. The figures are schematic in character, switch-hook contacts and the like being omitted.

In the circuit shown in Fig. 1, two similar condensers CA and CB connected in series and the two halves or microphone elements of the differential variable-resistance microphone M connected in series together form the arms of a four-armed bridge. The microphone may be constructed in one of the manners described in the application of William E. Goodwin, Serial No. 62,121, filed February 3, 1936. Line terminal L1 is connected via a choke coil CH to one junction point of the bridge and line terminal L2 is connected to the opposite junction point via winding (II) of a three-winding anti-sidetone transformer TR, the two junction points referred to being those where a condenser is connected to a microphone element. A condenser CC and the receiver R are connected in series between line terminal L1 and the said opposite junction point, the receiver being shunted by a circuit comprising an impedance in series with winding (III) of transformer TR. The impedance may as shown be a condenser CD in series with a non-inductive resistance S, in which case the resistance may be formed by a noninductive spool carried by or wound on transformer TR. The pair of junction points of the bridge which have not yet been referred to are connected to winding (I) of the transformer. Each of the condensers CA, CB, and CC may have a capacity of two microfarads and the condenser CD may have a capacity of

half a microfarad. A magneto bell B is connected between terminal L2 and the junction of condenser CC and receiver R.

When the instrument circuit is in the conversational condition, direct current is fed to the microphone from the exchange battery in a circuit which includes terminal L1, choke coil CH, the two halves or microphone elements of the microphone M in series, winding (II) of transformer TR, and terminal L2. When the microphone is affected by speech, alternating differences of potential are set up across winding (I) of the transformer and the resulting speech currents flowing through this winding are transmitted to the line by the usual transformer action. It will be seen that the feed currents flowing through the two halves or microphone elements of the microphone must always be equal since any steady direct current which passes through one must also pass through the other. It will further be seen that, since the impedances of the condensers CA and CB must of necessity change with frequency and these condensers are included in the circuit of winding (I) of the transformer, the said condensers may be arranged to play an important part in determining the response-frequency characteristic of the microphone system. With a three-winding anti-sidetone transformer of well-known type and with condensers of the value quoted we have found that the effect of the condensers is to cause a progressive weakening of the response as the frequency is reduced from about 500 cycles per second to a lower frequency.

In the circuit shown in Fig. 2, two similar condensers CA and CB and the two halves or microphone elements of the differential variable-resistance microphone M form a four-armed bridge which is similar to that of the circuit of Fig. 1. In this case also the microphone may be constructed in one of the manners described in the application previously referred to. Transformer TR with its windings (I), (II), and (III) and condensers CC and CD, receiver R, bell B, and resistance S correspond to the apparatus similarly designated in Fig. 1. The two junction points of the four-armed bridge where a condenser is connected to a microphone element are connected to the local battery LB. Each of the three condensers CA, CB, and CC may have a capacity of two microfarads and the condenser CD may have a capacity of half a microfarad. It will be seen that in this circuit also the feed currents flowing through the two halves or microphone elements of the microphone must always be equal since any steady direct current which passes through one must also pass through the other, and the condensers may be arranged to play an important part in determining the response-frequency characteristic of the microphone system. The choke CH would not always be provided, its object when present being to provide a low-resistance path for signal current in the case where the instrument circuit is used on a central battery signalling C. B. S. system. The condenser

CC is only essential in the case of a C. B. S. system.

In a modification of the circuit just described, only one condenser is associated with the microphone, the left-hand terminal of winding (I) of transformer TR being connected via this condenser to the centre point of the battery, which must of course consist in this case of an even number of cells. Here again any steady direct current which passes through one half or microphone element of the microphone must also pass through the other half or element.

We claim:—

1. In a substation telephone circuit, a microphone of the differential type having two microphone elements, a transformer, one line conductor connected to one of said microphone elements and the other line conductor connected in series with a secondary winding of said transformer to the other microphone element, a connection comprising a pair of condensers in series connected in bridge of said microphone elements, one terminal of the primary winding of said transformer connected to the midpoint between said two microphone elements, and the other terminal of said primary winding connected to the midpoint between said two condensers.

2. A substation telephone circuit comprising a transformer, a differential transmitter having two transmitter elements, a line, a circuit for said transmitter including one winding of said transformer and said two elements in series, said circuit connected to said line so that the direct current flow thereover must pass through said elements irrespective of the equalization of the resistance in said elements.

3. In a substation telephone circuit comprising a transformer, a differential transmitter having two fixed electrodes and a movable electrode, two condensers of equal capacity, a loop circuit including said electrodes and said condensers in series, a direct current feeding circuit for said transmitter, said feeding circuit connected to said loop circuit so as to bridge said condensers, and an output circuit including one winding of said transformer connected to said loop circuit so as to bridge the midpoint between said condensers and said movable electrode.

4. A substation common battery telephone circuit comprising a transformer, a differential microphone of the type having two fixed electrodes and a single movable electrode, a line over which microphone current is received, a circuit for said microphone including said electrodes and one winding of said transformer in series with said line, two condensers bridging said microphone electrodes, an output circuit including another winding of said transformer connected between said condensers and said movable electrode whereby the impedance of said condensers determine the response-frequency characteristics of said telephone circuit.
